MOTO METER GAUGE & EQUIPMENT CORPORATION, OF LONG ISLAND CITY, NEW
YORK, A CORPORATION OF DELAWARE

RETAINING DEVICE

Application filed July 6, 1927. Serial No. 203,743.

This invention relates to retaining devices for radiator caps of automobiles and more particularly to retaining means for preventing the removal and theft of such a radiator cap. The general object of the invention is to provide a new and effective retaining device which is simple in structure, economical to manufacture and easy to apply. Another object of the invention is to provide a simple and effective retaining device which may be installed merely by forcing one end part into the radiator cap and the other end part into the radiator neck.

The invention will be understood from the following description taken in connection with the accompanying drawings, in which:

Figure 1 is a sectional elevation illustrating a preferred form of the invention;

Figure 2 is a view in a plane perpendicular to the plane of the section in Figure 1; and

Figure 3 is a sectional view taken along the line 3—3 of Figure 1.

Referring to the drawings, the invention is illustrated in connection with a radiator cap 10 internally threaded to screw upon the threaded upper end of a radiator neck 11 having at its upper edge an internal annular flange 12. The securing device is shown as comprising a sheet metal member or plate 13 cut away at its circumference to provide branches or arms 14 having arcuate outer edges adapted to engage the threaded or circumferentially grooved inner wall of the radiator cap. Secured to the middle of the plate 13 is a chain 15 of which two links at the upper end thereof extend through a central opening in the member 13 and are upset outwardly to secure the chain to the plate or member 13. The radiator cap 10 may be equipped with any suitable device or instrument 22 which may be secured to the cap by a threaded portion thereof screwed into the top of the cap and locked in such position in any suitable manner. The chain 15 passes through a ring 17 forming part of the device 18 for locking the chain 15 to the radiator neck 11 and withdrawal of the chain from the ring 17 may be prevented by a split ring 19 attached to end links of the chain 15 and of such size as to be incapable of passing through the

opening of the ring 17. The device 18 may be unitary and includes, in addition to ring 17, arms 20 extending outwardly therefrom and then upwardly and outwardly. The ring 17 is flared outwardly from its lower edge to its upper edge so as not to interfere with the movement of the flexible connection or chain 15 as the latter is pulled up in shifting the radiator cap in various directions to positions such as indicated in Figure 2. It will be noted that at opposite sides of the ring 17 there are upwardly and outwardly flared lips 21 forming reinforcing flanges.

The device may be applied as follows:

The sheet metal member 13 may be forced up into the radiator cap 10 thus causing rearward bending of the outer edges of the arms 14 and subsequent springing of said rearwardly bent edges into the circumferential grooves of the threaded portion and lock the member 13 against removal especially by pulling the chain 15. A washer 23 may then be inserted in the cap 10. The device 18 may be forced downwardly into the neck 11, the arms 20 being sprung together sufficiently to permit them to pass the flange or rib 12 and then snapping outwardly into position beneath the same as soon as device 18 has been inserted far enough. The cap 10 may then be screwed on the top of the radiator neck 11.

It will be apparent that devices constructed according to the present invention may be applied very readily and will then effect a permanent locking connection between the radiator cap and the radiator neck. It should be understood that the chain or flexible connection 15 is of such length as to permit the radiator cap 10, when unscrewed, to be tilted sufficiently to one side to permit filling the radiator with water without interference by the radiator cap.

As herein disclosed, the outer ends or edges of the arms 14 of member 13 co-operate with the threaded inner wall of the radiator cap. It should be understood, however, that the cap may be provided with recesses, shoulders or grooves formed independently of screw threads such as those utilized for fastening the cap 10 on the neck 11. Furthermore, the upper ends of the arms 20 may co-operate

with any suitable formation at the inner lateral surface of the neck 11, for example, recesses or downwardly facing shoulders at the inside of the neck.

5 It should be understood that various changes may be resorted to within the scope of the invention and that portions of the improvements may be used without others.

What I claim is:

10 1. The combination with a radiator cap grooved circumferentially in the interior thereof, of radiator-cap-retaining means including an arched member adapted to extend across the cap constructed to yield in one direction at its edge to permit insertion into said cap and to engage the grooved interior surface of said cap and be locked permanently and positively against removal.

15 2. The combination with a radiator cap grooved circumferentially in the interior thereof, of radiator-cap-retaining means including a sheet metal member having outwardly extending spring arms with arcuate ends to engage the grooved portion of the interior of said cap and be bent back during insertion into the cap and when inserted to grip said grooved portion and spread to prevent removal.

20 3. Means for attaching a radiator cap recessed at its lateral interior surface to a radiator neck having a downwardly facing shoulder formation at the interior thereof, including a metal plate to be sprung into said cap and effect locking engagement with the recessed inner surface to prevent removal of the plate, a device with spring portions arranged to be sprung inwardly in inserting said device in said neck and to snap beneath said shoulder formation and lock said device against removal, and a flexible connection attached to said plate and said device at their centers.

25 4. Means for attaching a radiator cap circumferentially grooved internally to a radiator neck having a downwardly facing shoulder formation at the interior thereof, including a metal plate to be sprung into said cap with backwardly sprung edges to engage the internal grooved portion of the cap and prevent removal of the plate, a device with upstanding spring arms arranged to be sprung inwardly in inserting said device into said neck and to snap beneath said shoulder formation and be locked against removal, and a flexible connection between said plate and said device and attached centrally thereto.

30 5. The combination with a radiator neck having an internal annular rib, of a radiator-cap-retaining device including an inverted U-shaped member comprising a body portion nearly as wide as the mouth of the neck and legs adapted to extend upwardly closely adjacent the inner wall of the neck throughout their entire lengths to be sprung past said

rib and expanded beneath the same to lock said device against removal, and means forming a permanent, lost motion connection between the cap and said member.

35 6. The combination with a radiator neck having a downwardly facing annular shoulder, of a radiator-cap-retaining device including an inverted U-shaped device having a central body portion provided with an opening and upstanding and outspread spring arms sprung inwardly in inserting the device and snapping outwardly beneath said shoulder when carried past the same, and means forming a permanent lost motion connection between the cap and said member including a flexible connector permanently secured to the cap and passed downward through the opening in said device and a member secured to the lower end of the connector and permanently of too great size to be drawn upward through said opening.

40 7. The combination with a radiator neck having a downwardly facing shoulder formation, of a radiator-cap-retaining device having a central ring portion and spring arms extending outwardly and then upwardly and outwardly, said arms being sprung inwardly in inserting said device and snapping into position beneath said shoulder formation, a flexible connection between said cap and said device passing through said ring, and means attached to the lower end of said flexible connection to prevent withdrawal of the chain from the ring, said ring being flared outwardly from the bottom to the top.

45 8. Means for locking a radiator cap to a radiator neck including a central flexible portion, a downwardly concave device at one end automatically locked to said cap by insertion therein, and an upwardly concave device at the other end automatically locked to said radiator neck by insertion therein.

In testimony whereof I have affixed my signature to this specification.
